(57) **CLAIM**

The ornamental design for an divisible multi-well plate, as shown and described.

DESCRIPTION

FIG. 1 is a front perspective view of a frame member of a divisible multi-well plate according to one embodiment;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is an enlarged view of the encircled area 8 of FIG. 2;

FIG. 9 is an enlarged view of the encircled area 9 of FIG. 6;

FIG. 10 is a front perspective view of the divisible multi-well plate view in an attached state;

FIG. 11 is a front view thereof;

FIG. 12 is a rear view thereof;

FIG. 13 is a right side view thereof;

FIG. 14 is a left side view thereof;

FIG. 15 is top view thereof;

FIG. 16 is a bottom view thereof;

FIG. 17 is an enlarged view of the encircled area 17 of FIG. 11;

FIG. 18 is an enlarged view of the encircled area 18 of FIG. 15;

FIG. 19 is an exploded front perspective view thereof, showing one section of an 8-well strip being separated;

FIG. 20 is a front perspective view of a divisible multi-well plate according to another embodiment;

FIG. 21 is a front view thereof;

FIG. 22 is a rear view thereof;

FIG. 23 is a right side view thereof;

FIG. 24 is left side view thereof;

FIG. 25 is a top view thereof;

FIG. 26 is a bottom view thereof;

FIG. 27 is an enlarged view of the encircled area 27 of FIG. 21;

FIG. 28 is an enlarged view of the encircled area 28 of FIG. 25;

FIG. 29 is an exploded front perspective view thereof, showing one section of an 8-well strip being separated;

(Continued)

FIG. 30 is a front perspective view of one section of the 8-well strip of the divisible multi-well plate shown in FIG. 19;

FIG. 31 is a front view thereof;

FIG. 32 is a rear view thereof;

FIG. 33 is a right side view thereof;

FIG. 34 is a left side view thereof;

FIG. 35 is a top view thereof; and,

FIG. 36 is a bottom view thereof.

The broken lines represent portions of the divisible multi-well plate that form no part of the claimed design.
